Edmund M. Pond Inventor
By his Attorney A. V. Burkhardt

UNITED STATES PATENT OFFICE.

EDMUND MORSE POND, OF RUTLAND, VERMONT.

SURGICAL BANDAGE.

974,294.

Specification of Letters Patent. Patented Nov. 1, 1910.

Application filed September 16, 1908, Serial No. 453,247. Renewed March 25, 1910. Serial No. 551,583.

To all whom it may concern:

Be it known that I, EDMUND MORSE POND, a citizen of the United States of America, and a resident of Rutland, county of Rutland, State of Vermont, have invented certain new and useful Improvements in Surgical Bandages, of which the following is a specification.

My invention relates to a composition of materials useful for a variety of purposes.

It comprises a mixture of gelatin and glycerin with a core of woven fabric, fine wire cloth, gauze or other textile material, and a waterproof backing, particularly suitable for use as a surgical bandage or dressing.

I find that by varying the proportions of the gelatin-glycerin mixture, I can produce compositions of varying degrees of hardness which would operate in correspondingly different ways as desired when applied to a wound or to the surface of the patient's body.

The best form of structure embodying my invention and certain modifications are illustrated in the accompanying sheet of drawing, in which:

Figure 1 is a detail view of a specimen of my material with parts broken away to show the woven fabric. Fig. 2 shows in cross section a form useful as a surgical bandage or dressing. Fig. 3 shows a similar form in which wire cloth is used. Fig. 4 shows a modified form in which a major portion of the gelatin-glycerin compound is on one side only of the fabric.

Throughout the drawings like reference figures indicate like parts.

1 is the mixture of gelatin and glycerin, 40 and 2 is the core of woven material (see Fig. 1).

As shown in Fig. 2 the structure of Fig. 1 has an outer covering 9 of thin india rubber or other waterproof material which does not 45 show in Fig. 1.

In Fig. 3, a core of wire cloth 8 is substituted for the core 2 of ordinary gauze or other textile material shown in Fig. 1. The wire cloth serves the purpose of a splint for 50 fixation and produces a combined surgical dressing and splint. The gelatin-glycerin compound is slowly absorbed by the flesh of the patient and is beneficial in its action.

While the best results for most purposes 55 are secured by embedding the woven fabric in the compound, it may be advisable in

some cases to have a major portion of the gelatin-glycerin compound on one side only of the fabric, as shown in Fig. 4. The gauze or other woven material gives strength to 60 the fabric, and if of textile material, its absorbent properties enable it to take up some of the other materials and give permanency of form to the whole structure.

Of course any desired medication may be 65 used with the gelatin-glycerin compound. The combining of gelatin and glycerin making it possible to vary the hardness of the compound as above stated, of course varies 70 its resistance to liquefaction by the heat and moisture of the human body so as to produce a variety of medicinal effects.

In use the heat and moisture of the body melt and liquefy the compound according to 75 its degree of hardness, and the waterproof backing preventing its escape in a direction away from the surface of the wound, it is held in contact therewith. The meshes of the gauze also tend to hold the liquid or semi-liquid material in contact with the 80 skin by which it is slowly absorbed. The gelatin-glycerin composition by reason of its predetermined degree of hardness dissolves slowly so that prolonged medication is obtained. A more rapid absorption if 85 desired is produced by making the material more liquid, that is by increasing the percentage of glycerin until as high as 80% glycerin to 20% gelatin may be attained. The gauze also exerts a restraining action 90 in the tendency of the material to flow when melting, holding the same by capillary attraction and mechanical obstruction. If the gauze were not used the material would run much more rapidly and could not be held 95 in contact with the wound so long. The gauze also performs an important function in enabling the completed structure to hold its form and shape during handling and transportation so that it can be marketed successfully.

If it were not for the gauze the ordinary glycerin-gelatin compound would tend to melt and run when subjected to ordinary high atmospheric temperatures. 100

In using the forms shown in Fig. 3, 105 the wire cloth has the necessary stiffness to serve as a splint in the case of application to an ordinary fracture such as a fractured wrist. The glycerin-gelatin composition has its medical action in reducing inflammation 110 and is absorbed by the flesh to the benefit of the patient, these materials, being of

animal origin, really acting as a flesh food. In case of a fracture with an open wound, the material could be perforated as shown in my application No. 398,796, filed Oct. 23, 1897, thereby supplying the necessary drainage and producing the other effects set forth in my said prior application.

The form shown in Fig. 4 has the advantage of greatest indestructibility in transportation, the gelatin-glycerin composition being nearly all protected by the waterproof backing on one side and the gauze facing on the other. This form could be used where the slow dissolution of the compound was desired, producing prolonged but not rapid action of the compound on the flesh.

My improved surgical dressing may also be used for skin diseases or as a blister. It may be employed to produce absorption of drugs to underlying organs, such as enlarged glands of the neck. In such case the composition might be impregnated with iodin which would penetrate through the flesh and reach the gland, destroying infection thereof and aiding the recovery of normal conditions. It can be used as a dressing for rheumatism by combining with it salicylic acid or its compounds. It can be applied to treat bronchial and other chest diseases.

Having, therefore, described my invention, I claim:

1. A surgical bandage and dressing comprising in combination a textile fabric, a body of material readily soluble in water at the normal temperature of the human body, in which the textile fabric is embedded, and a water-tight backing of waterproof material.

2. A surgical bandage and dressing comprising in combination a textile fabric, a readily soluble composition of glycerin and gelatin in which the textile fabric is embedded, and a water-tight backing of waterproof material.

3. A surgical bandage and dressing comprising in combination a textile fabric, a readily soluble composition of 75 parts glycerin and 25 parts gelatin in which the textile fabric is embedded, and a water-tight backing of waterproof material.

4. A surgical bandage and dressing com-

prising in combination a section of wire cloth, a body of material readily soluble in water at the normal temperature of the human body, in which the wire cloth is embedded, and a water-tight backing of waterproof material.

55

5. A surgical bandage and dressing comprising in combination a section of wire cloth, a readily soluble composition of glycerin and gelatin in which the wire cloth is embedded, and a water-tight backing of waterproof material.

60

6. A surgical bandage and dressing comprising in combination a section of wire cloth, a composition of 75 parts glycerin and 25 parts gelatin in which the wire cloth is embedded, and a water-tight backing of waterproof material.

65

7. A surgical bandage and dressing comprising in combination an open mesh textile fabric, a body of material readily soluble in water at the normal temperature of the human body in which the textile fabric is embedded, and a water-tight backing of waterproof material, the textile fabric being adjacent to the surface of said body of material opposite from that to which the waterproof backing is applied.

70

8. A surgical bandage and dressing comprising in combination an open mesh textile fabric, a readily soluble composition of glycerin and gelatin in which the textile fabric is embedded, and a water-tight backing of waterproof material, the textile fabric being adjacent to the surface of the composition opposite from that to which the waterproof backing is applied.

75

9. A surgical bandage and dressing comprising in combination an open mesh textile fabric, a composition of 75 parts glycerin and 25 parts gelatin in which the textile fabric is embedded, and a water-tight backing of waterproof material, the textile fabric being adjacent to the surface of the composition opposite from that to which the waterproof backing is applied.

80

Signed at New York, N. Y., this 15th day of Sept., 1908.

EDMUND MORSE POND.
